UNITED STATES PATENT OFFICE.

EDWARD COLLINS, OF NEW YORK, ASSIGNOR OF ONE HALF TO JAMES K. FROTHINGHAM, OF BROOKLYN, N. Y.

SCROLL-SAWING MACHINE.

SPECIFICATION forming part of Letters Patent No. 340,097, dated April 20, 1886.

Application filed June 1, 1885. Serial No. 167,361. (No model.)

To all whom it may concern:

Be it known that I, EDWARD COLLINS, a citizen of the United States, and a resident of New York city, county, and State of New York, have invented a new and useful Improvement in Scroll - Sawing Machines, of which the following is a specification.

The object of my invention is to produce a scroll-sawing machine which is so constructed that lightness, cheapness, durability, and effectiveness are attained.

Referring to the drawings, Figure I is a side elevation of my improved machine shown in section. Fig. II is a plan view of the same. Fig. III is an end view of same. Fig. IV is a detached sectional view of one of the saw-arms, showing it when made of cast metal. Fig. V is a front view showing a modified mode of strengthening the saw-arms.

20 A represents a vertical post, made of wood or iron. Onto this post is fastened at *a* the two metallic guide-brackets B B, which are provided with holes *d d*, through which slide the guide-rods C C. These brackets are fastened 25 to the post by screws *e e*. The rods C C can be made hollow or solid and of metal or wood. The holes *d d* can be faced with any anti-friction metal, to lessen the friction created by the movement of the rods through the said holes.

30 To these rods C C are fastened two saw-arms, F F, and they are placed at any convenient position and distance on said rods that use may suggest. These arms F F can be made of cast metal, as shown in Fig. IV; but for lightness

35 I construct them of two strips of wood, E E, held together by stay-bolts. Where the rods C C pass through the strips E E, I insert sleeves, G G, which are held fast to the strips in any convenient manner. Through these

40 sleeves the rods pass, and also through these sleeves are the arms F F, fastened to the rods, to be hereinafter more fully described. Where the saw H is attached to strips E E of the arms F F, I also place sleeves I I, through which

45 pass the hooks *a*, and to which the saw is attached. By constructing the arms F F in this manner lightness and strength are attained. The arms F F are fastened to rods C C by bolts H H, which pass through the sleeves G G and

50 said rods. The bolts *h h* are made to extend

rearward and are connected to sliding bolts *i i*, which are constructed to slide in the guideways *k k*, fastened onto the post A.

L is a stay-rod, fastened to the sliding blocks *i i* and to the arms F F at *f*. This stay-rod 55 is strengthened in the center by rod *o*. The object of this construction is to strengthen the arms F F and to shift the strain from the same onto the post A.

In case the arms F F are made very long 60 they may be strengthened by means of a rod, W, fastened to the extreme outer ends of the said arms, and connected by sliding blocks *w*, sliding in guideways *w*, fastened to a post, *w*, 65 extending from the floor and to a bracket, *w*, extending from the ceiling. (See Fig. 5.)

M is a table pivoted to bracket-arms N by pivot-pin *n*, said bracket-arms being cast or otherwise fastened to the post A. These bracket-arms are made of iron and joined together at *m*, just underneath the table, by cross-pieces *m*. The table can be tilted on any angle by the screw-bolt *n*, which is attached to the auxiliary bracket V, cast onto the bracket-arms N. To further support the table, I employ 75 the leg O, which is pivoted to the pivot-pin *n*.

The saw H is fastened to the arms F F by aid of the screw-bolts *a*, which, as before stated, pass through the sleeves I I. These screw-bolts are provided with thumb-screws 80 *s*, by which the saw H can be tightened as use may require.

P is an opening through the table, through which the saw passes.

R is an air-cushion to be used to take up the 85 fall of the saw and all the movable parts. It consists of a cylinder, *r*, which is fastened to the post A by screws. Into this cylinder is placed the plunger *r*, which is attached to one of the rods C. The bottom of this cylinder *r* 90 is provided with a valve, *r*, having stem *r*. Now, when the rods C rise, they carry with them the plunger *r*, which movement draws air into the cylinder *r*. When the rods C come down, the plunger compresses the air in the 95 cylinder, and prevents the downward movement being too rapid. This being attained, the movement of the saw either upward or downward will be the same and uniform. The saw is moved up and down by the connecting- 100

rod S, which is connected to one of the arms F in any suitable manner, and to the crank-wheel T.

Having thus described my invention, I desire to claim—

- 5 1. In a scroll-sawing machine, the movable rods or tubes C C, fastened to the saw arms F F, and sliding in guide-brackets B B, secured to the post A and operated by crank-rod S, substantially as and for the purpose set forth.
- 10 2. In a scroll-sawing machine, the saw-arms F F, constructed as described, in combination with the movable tubes or rods C C, held to the post A by brackets B B, and operated and held in position by crank S, substantially as and for the purpose set forth.
- 15 3. In a scroll-sawing machine, the combina-

tion of the rods or tubes C C, having fastened thereto the arms F F, the guide-brackets B B, secured to post A, the crank-rod S, the crank T, 20 placed at the upper end of the machine, the air-cushion R, placed at the bottom and underneath the tubes C C, the tilting table M, attached to bracket N, and the bracket L, attached to post A, substantially as and for the purpose set 25 forth.

In testimony that I claim the foregoing as my invention I have signed my name, in presence of two witnesses, this 16th day of August, 1884.

EDWARD COLLINS.
